[57] CLAIM

The ornamental design for a seat, substantially as shown and described.

DESCRIPTION

FIG. 1 is a three-quarter perspective view of a seat in accordance with the present invention viewed from the front;

FIG. 2 is a three-quarter perspective view from one side of the embodiment illustrated in FIG. 1; and

FIG. 3 is a three-quarter perspective view from the rear of the seat shown in FIGS. 1 and 2.

The side of the seat not shown in FIG. 2 is a mirror image of the side shown.

FIG. 1

FIG. 2

FIG. 3
